PACK FOR FRAGILE ARTICLES

Fred C. Harper, Waterville, Maine, assignor to
Keyes Fibre Company, Portland, Maine, a cor-
poration of Maine

Application January 10, 1948, Serial No. 143,637

Term of patent 14 years

(Cl. D58—13)

To all whom it may concern:

Be it known that I, Fred C. Harper, a citizen of the United States, residing at Waterville, in the county of Kennebec, State of Maine, have invented a new, original, and ornamental Design for a Pack for Fragile Articles, of which the following is a specification, reference being had to the accompanying drawing, forming part thereof.

Fig. 1 is a perspective view of a pack for fragile articles showing my new design, the pack being shown in open position;

Fig. 2 is a perspective view thereof in closed position; and

Fig. 3 is a plan view of the pack in fully open position.

I claim:

The ornamental design for a pack for fragile articles, as shown.

FRED C. HARPER.
